PLATEN ADJUSTING MEANS FOR
TYPEWRITERS.

Francis U. Ritz, Poughkeepsie, N. Y., assignor to
International Business Machines Corporation,
New York, N. Y., a corporation of New York

Application March 18, 1949, Serial No. 82,348

6 Claims. (Cl. 197—149)

1

This invention relates to typewriting machines. The broad object of the present invention is to provide means for adjusting the platen of a front strike typewriting machine to accommodate for varying thicknesses of manifold packs.

An object is to provide a simple and effective means of moving the platen toward and away from the typing position commensurate with the number of copies to be made and the combined thickness of the sheets comprising the manifold pack.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a plan view partly in section of a carriage embodying the present invention.

Fig. 2 is a vertical section on the line 2—2 in Fig. 1.

Fig. 3 is a vertical section on the line 3—3 in Fig. 1.

The carriage comprises the left-hand side plate 10 and the right-hand side plate 11, which are integrally joined together by a channel shaped member 12, which may be welded or brazed to the side plates 10 and 11. The plates are also joined together by a tie rod 13, by the marginal stop rod 14, and by the tabulating stop rod 14a. Pivotally mounted between the plates 10 and 11 are the paper bail arms 15 supporting the cross shaft 15a on which are rotatably and longitudinally adjustably mounted the paper bail rollers 16. The channel shaped member 12 acts as a guide for the usual anti-friction rollers 17 by means of which the carriage is mounted on the guide rails 18 (Fig. 2).

Slidably mounted on the plates 10 and 11 is 40 a pair of plates 19 each having inclined parallel slots 19a guided by circumferential grooves in the studs 20 carried by the plates 10 and 11. The lowest two slots 19a are open while the others are key hole shaped to permit removal of the plates 19 when necessary by sliding the plates toward the front of the machine until the larger portions of the studs 20 enter the enlarged portions of the key hole slots thus permitting the plates 19 to be removed from the studs 20.

5 There is one open slot 19a and two key hole shaped slots 19a for each plate 19. These plates removably rotatably support the platen 21 and have associated therewith means for adjustably sliding the plates on the studs 20 to move the platen toward and away from the printing point.

The platen may be of the usual construction and includes the usual platen rotating knobs 21a and the line spacing ratchet 21b. The platen may be provided with line spacing mechanism of the type disclosed in Patent 1,957,322.

10 The platen is removably mounted in the plates 19 by means of open slots 19b which act as cradles for the platen shaft and is retained in these slots by means of the platen latches 22 pivoted to the plates 19 at 19c. The latches are spring urged into latching position by torsion springs 23 which engage pins on the latches 22 and urge the latches into platen retaining position. The pivots for the arms 15 of the paper bail are carried by plates 19 so that the paper bail will be shifted with the platen. The plates 10 and 11 are cut away to permit removal of the plates by disengaging the latches 22.

15 Pivoted at 19a, 11a (Figs. 2 and 3) are the usual carriage release levers 24 which have finger pieces 24a by means of which the levers 24 may be rocked clockwise (Fig. 2) to actuate the usual release bail 25 in a counterclockwise direction in a well known way. Journalled in the plates 10 and 11 is the shaft 26 to which is secured the arm 27. The shaft 26 supports the usual paper deflector which is provided with pressure rollers coacting with the platen to press papers wrapped around the platen against the platen. This paper deflector is not shown in the present instance as it forms no part of the present invention and its showing in the drawings would be confusing.

20 The shaft 26 may be rocked counterclockwise (Fig. 2) to release the paper deflector by means of the lever 28 which is pivotally connected at 29a to an arm 29 and at 27a to the arm 27. Arm 29 is pivoted at 10a to plate 10. When the lever 28 is drawn to the right manually (Fig. 2), the pivot 29a swings to the right and the lever 28 swings clockwise thereby depressing the arm 27 against the tension of the usual spring actuating the paper deflector.

25 Mounted on the plates 10 and 11 are the plates

30, each of which is bifurcated to slide on a shouldered stud 10b, 11b carried by the plates 10, 11 while the other end of each plate has a round hole by means of which the plates 30 are pivoted on eccentric shoulders in studs 31 carried by the associated plate 10 or 11. Journalled in the plates 30 is the shaft 32 formed with two eccentric cams 32a smoothly fitting open vertical slots in the plates 19. It is evident that rotation of the shaft 32 will result in the plates 19 sliding on the pins 20. The plates 30 and the shouldered studs 31 are provided for the purpose of initially adjusting the platen for parallelism after which the studs 31 are secured by means of clamping screws 33 to retain the adjustment.

Secured to the shaft 32 at the right-hand end of the carriage (Fig. 1) is the lever 34. This lever has a pin 34a or bump formed therein capable of registering with any one of a series of holes 35a in an arcuate index plate 35 mounted on the plate 11 by screws 11b and 33 and having the stop lugs 35b for limiting the extent of rotation of lever 34 in either direction. The pin or bump 34a may be sprung out of the holes 35a and shifted into register with another hole. With the lever 35 in the position of Fig. 3, the eccentric 32a hold the plates 19 in their most forwardly position or left-hand position relative to the type guide in which the distance of the platen from the type guide is at a minimum. When the lever 34 is rotated clockwise (Fig. 3) to the opposite extreme the plates 19 will be drawn to the right or rearwardly of the type guide and shift the platen an extent determined by how far the lever 34 is moved.

For a single sheet or perhaps a single carbon copy, the lever will be set in the position shown in Fig. 3 or with the pin 34a in the next adjacent hole 35a on the right. In the case of a very thick manifolding pack, the lever 34 will be shifted to one of the extreme right-hand holes (Fig. 3) thereby moving the platen an extent commensurate with the thickness of the manifolding pack.

Secured to the plates 10 and 11 are the half housings 36 to which are pivoted, at 36a, the half housings 37, the housings 36, 37 forming enclosures at each end of the carriage for the various levers and other parts associated with the ends of the carriage. The housings 37 are provided with suitable slots and openings for the carriage release levers 24, the paper deflector release lever 28, and the lever 34 for adjusting the platen to the thickness of the manifolding pack. There is also provided a line spacing control lever 38 and the left-hand housing 37 is provided with slots to accommodate this lever. This line space lever functions the same as in Patent 1,957,322.

While there have been shown and described and pointed out the fundamental novel features of the invention as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In combination, a carriage having a pair of parallel side plates, mounting studs on said plates, a pair of platen supporting plates each mounted on said studs for sliding movement parallel with said side plates at right angles to the movement of the carriage; a shaft rotatably mounted in

side plates and having a pair of cams, each cam being received in a slot formed in one of the supporting plates whereby rotation of the shaft effects the aforesaid movement of said plates, a manual setting lever secured to said shaft, and an indexing plate mounted on said carriage and coacting with said lever to releasably retain said lever in its set positions.

2. In combination, a carriage having a pair of parallel side plates, mounting studs on said plates, a platen, a pair of platen supporting plates each mounted on said studs for sliding movement parallel with said side plates at right angles to the movement of the carriage; a shaft having a pair of cams, each cam being received in a slot formed in one of the supporting plates whereby rotation of the shaft effects the aforesaid movements of said plates, means to mount said shaft in said side plates for adjusting said platen into parallelism with the movement of the carriage, a manual setting lever secured to said shaft, and an indexing plate adjustably secured to said carriage and coacting with said lever to releasably retain said lever in its set positions.

3. In combination, a carriage having a pair of parallel side plates, mounting studs on said plates, a platen, a pair of platen supporting plates each mounted on said studs for sliding movement parallel with said side plates at right angles to the movement of the carriage; a shaft having a pair of cams, each cam being received in a slot formed in one of the supporting plates whereby rotation of the shaft effects the aforesaid movement of said plates, means to mount said shaft in said side plates for adjusting said platen into parallelism with the movement of the carriage, a manual setting lever secured to said shaft, and an indexing plate adjustably secured to said carriage and coacting with said lever to releasably retain said lever in its set position, said shaft mounting means including a pair of bearing plates slidably mounted on said side plates and eccentric studs, one for each side plate, carried by said side plates, and pivotally supporting said bearing plates for adjustably shifting said bearing plates.

4. In combination with the carriage of a typewriting machine, a platen, a pair of platen supporting plates mounted in said carriage for limited movement at right angles to the movement of the carriage and having means for rotatably supporting said platen with its axis parallel with the movement of the carriage, a shaft extending parallel with the axis of the platen and having cams received in suitable bearings in said plates, bearing plates for supporting said shaft in said carriage and individually adjustably movable to shift the axis of the shaft sufficiently to place the axis of the platen parallel with the movement of the carriage, means to secure said bearing plates in adjusted positions, and indexing means for said shaft including a manual lever having a connection to said shaft for adjustably rotating said shaft.

5. A carriage for typewriters and other office machines comprising a main member, three pairs of plates, one plate of each pair being located at the ends of the main member, one pair of plates being secured to the ends of said member and movably supporting the other two pairs for movement in unison at right angles to the carriage movement, a platen rotatably mounted in one of said movable pairs, means mounted on the other of said movable pairs for adjustably moving said one movable pair at right angles to the carriage movement, and means for adjustably

moving said other movable pair relative to the fixed pair.

6. A carriage for typewriters and other office machines comprising a main member, three pairs of support members, one member of each pair being located at the ends of the main member, one pair of support members being secured to the ends of said member and movably supporting the other two pairs for movement in unison at right angles to the carriage movement, a platen rotatably mounted in one of said movable pairs, means mounted on the other of said movable pairs for adjustably moving said one movable pair at right angles to the carriage movement, and means for

adjustably moving said other movable pair relative to the fixed pair.
